UNITED STATES PATENT OFFICE

150,432

DESIGN FOR A TIRE

Leonard John Lambourn, Erdington, Birmingham, and Frank Bernard Jones, Castle Bromwich, England, assignors to Dunlop Tire and Rubber Corporation, Buffalo, N. Y., a corporation of New York

Application January 28, 1947, Serial No. 136,483
In Great Britain August 29, 1946

Term of patent 14 years

(Cl. D90—20)

To all whom it may concern:

Be it known that we, Leonard John Lambourn, a subject of the King of Great Britain, resident of 11 Poppy Lane, Erdington, Birmingham, and Frank Bernard Jones, a subject of the King of Britain, resident of 2 The Green Castle Bromwich, Warwickshire, respectively, have invented a new, original, and ornamental Design for Tire, of which the following is a specification, reference being had to the accompanying drawings, forming a part thereof.

Fig. 1 is a perspective view, and

Fig. 2 is a plan view of a section of a tire showing our new design.

We claim:

The ornamental design for a tire, as shown.

LEONARD JOHN LAMBOURN.
FRANK BERNARD JONES.
